Peter Benenfeld, Bronx, N.Y., assignor to Peter's Bag Corporation, Bronx, N.Y., a corporation of New York

Filed Apr. 26, 1968, Ser. No. 11,634

Term of patent 14 years

Int. Cl. D8—03

U.S. Cl. D8—154

FIG. 1

FIG. 2

FIG. 4

FIG. 1 is a top perspective view of a combined luggage handle and attachment bar therefor, showing my new design;

FIG. 2 is an enlarged side elevation thereof, the side opposite being identical thereto;

FIG. 3 is a top plan view thereof; and

FIG. 4 is an elevation thereof as seen from either end. The fragmentary broken line showing of a piece of luggage in FIGS. 1—4 is for purposes of illustration.

I claim:

The ornamental design for a combined luggage handle and attachment bar therefor, as shown and described.
